UNITED STATES PATENT OFFICE.

ALBERT J. HANISCH, OF OAK PARK, ILLINOIS.

BLANKET FOR HORSES.

1,239,478.

Specification of Letters Patent. Patented Sept. 11, 1917.

Application filed November 27, 1915. Serial No. 63,887.

To all whom it may concern:

Be it known that I, ALBERT J. HANISCH, a citizen of the United States, residing at Oak Park, in the county of Cook and State 5 of Illinois, have invented a certain new and useful Improvement in Blankets for Horses, of which the following is a specification.

This invention relates to blankets for horses, etc., whether called "storm blankets," 10 "kidney covers," or "horse covers." The object of the invention is to provide the device of this character, which is very satisfactory in use and operation because it possesses singly or together novel forms of hame 15 leathers, trace carriers and adjustable front strap fasteners.

The invention consists in numerous features and details which will be hereafter fully described and claimed.

Referring to the drawings, in which similar numerals indicate the same parts throughout the several views,

Figure 1 is a picture of a horse having a blanket embodying all the features of this 25 invention applied thereto.

Fig. 2 is a plan view of a blanket removed from the horse and spread out.

Fig. 3 is a sectional view of one side of the front strap fastener device taken on the 30 line 3—3 of Fig. 2, while

Fig. 4 is a corresponding view of the other half of this device taken on the line 4—4 of Fig. 2.

Fig. 5 is a sectional detail view of the improved trace carrier, lazy strap or tug strap and its method of attachment to the blanket, taken on the line 5—5 of Fig. 2.

Blankets of this type are preferably made with an outer layer of waterproof material 40 10, whether of rubber, waterproof duck or the like is wholly immaterial, the same being lined with a plurality of layers 12 of material, well understood in the art, designed to afford warmth to the animal to which the 45 blanket is applied.

In applying the front strap fasteners of this invention to such a blanket, pieces of leather 14 and 16 of suitable size are provided for attachment directly to the blanket 50 material by stitches 18 or other suitable securing devices of such a character that they do not present rough surfaces on the inside of the blanket adjacent to the body of the animal. These leather pieces 14 and 16 are 55 provided with vertical slots 20 through which leather loops 22 and 24 may be re-

spectively inserted and secured in place by rivets 26 which, as clearly shown in Figs. 3 and 4, do not enter the innermost sheet 12 of the blanket material. The result of this 60 construction is that these loops 22 and 24 are secured by the rivets to the cloth, duck and leather members 14 and 16 without the inner ends of the rivets ever coming in contact with the animal to which the blanket is 65 applied, as is the case where loops of leather are riveted entirely through a blanket as has heretofore been the practice in the art.

One of these loops, as 22, is provided with, say, a ring 28 in which a snap 30 may engage, while the other loop, as 24, is provided with a buckle 32 in which the front fastener strap 34 proper carrying the above mentioned snap 30 is adjustably securable in the ordinary manner.

By the construction just described, this complete adjustable front strap fastening device is secured to the blanket in a very secure and satisfactory manner without providing any part of a rough or otherwise 80 harmful character contacting the body of the animal or object, such as an automobile, to which the blanket is applied.

Referring now to the trace carrying device, particularly illustrated in Fig. 5, the 85 outer surface of the blanket is provided on each side with a reinforcing plate 40 of leather, secured in place by a stitching or other suitable means. This reinforcing member 40 and the sheets of blanket material 10 and 12 have cut in them slots 42 and 44 running parallel to each other and parallel to the length of the blanket so that a loop 46 is provided over which a sliding strap 48 is passed, as clearly appears 90 in Fig. 5. This strap 48 carries at one end a ring 50 and at the other end a snap 52, these two parts being attachable and detachable together after being placed over a harness trace, wagon shaft or thill, or other 95 object to which the blanket is to be secured to prevent its being blown off from the particular thing on which it is used.

The structure just described is advantageous in that the strap 48 is much more 105 securely fastened to the blanket than it would be were it riveted in the ordinary manner; in that as the strap assumes different positions at different times, the pull and consequently the wear on the strap is 110 much more evenly distributed than when the strap is rigidly secured in one place, thereby

giving it longer life; and finally, in that the strap is readily adjustable with reference to the blanket to suit the convenience of the user in applying the device to a trace or other object about which the strap 48 is to be secured.

By equipping the blanket with the hame leathers 60 and 62, the same being strips of leather of the shape shown, sewed in place, the blanket is protected against wear from the hames of the harness.

Having thus described my invention, what I claim as new and desire to secure by Letters Patent, is:—

- 15 1. In a device of the class described, the combination of a blanket, a plate of reinforcing material secured to one side of the blanket, a loop formed in the blanket by having parallel slots cut in said reinforcing material and the blanket material, and a strap located on the opposite side of the

blanket from the reinforcing plate and slideable over said loop, for the purposes set forth.

2. In a device of the class described, the combination of a blanket member, a reinforcing plate 40 on one surface thereof, a loop 46 formed in the material of said plate and said blanket, bent outward from the surface of the blanket toward the side 30 thereof opposite to that on which said plate 40 is located, and a strap slideable through said loop and bearing upon the portion of the loop which is faced by a portion of the reinforcing plate 40.

In witness whereof, I have hereunto subscribed my name in the presence of two witnesses.

ALBERT J. HANISCH.
